UNITED STATES PATENT OFFICE.

GEORGE WILLIAM BERRY, OF LEEDS, ENGLAND, ASSIGNOR OF ONE-HALF TO CHARLES JOSEPH RHODES, OF WAKEFIELD, ENGLAND.

MACHINE FOR CLOSING OR SEALING RECEPTACLES.

Application filed March 19, 1925, Serial No. 16,669, and in Great Britain March 28, 1924.

This invention relates to machines for closing receptacles and more particularly for closing cans, tins, and the like which have already been charged or filled, such for example as tins of condensed milk, and the object is to provide a simple and efficient machine by which, if desired, a plurality of such receptacles may be dealt with simultaneously, the method of closure adopted being for example as disclosed in the specification pending application No. 663,242 filed 15th September, 1923, or method similar thereto.

According to this invention the sealing operation is effected in two successive stages by means of two sets of dies or plurality of such sets according to the number of receptacles being dealt with.

The invention comprises a support such as a bed or table in which slide one or more reciprocating feed members adapted to support the receptacles and convey them in succession first below a lid containing a chute and then to two following die positions at the first of which the lid is applied and at both of which closure is effected in two successive stages by means of dies or the like acting directly on the lids.

The invention also comprises other details of construction, arrangement and combination of parts as set forth in appended claims and hereinafter described with reference to the accompanying drawings in which:

Fig. 1 is a front elevation of the machine; Fig. 2 a side elevation thereof; Fig. 3 is a plan view of the feed members and associated parts; Fig. 4 is a partial plan view of the lid applying means on an enlarged scale and Fig. 5 a cross section on the line 5-5 of Fig. 4.

The machine shown in the drawings comprises a bed or table *a* on or in which are formed a number of raceways or tracks *b* according to the number of receptacles to be dealt with simultaneously four of such tracks being indicated in Fig. 1. Above said table is a vertically reciprocating ram or die head *c* carrying the two series of dies *c*¹ *c*² for the first and second sealing operations above referred to. The die head is suitably guided by vertical pillars *d* say four in number as shown, and operated as by side rods *d*¹ and eccentrics *d*², the latter

being mounted on a main driving shaft *e* 55 below the bed *a*.

The raceways above mentioned contain reciprocating feed slides *f* which extend forward to approximately the position of the second dies and at their rear are provided with stepped portions or abutments *f*¹ *f*² *f*³ against which the receptacles are placed for spacing them, the shoulders being spaced according to the distances between closure or lid carrying hopper, hereinafter mentioned, and the centres of the dies. Said slides feed the receptacles through the machine, thus at the first position (I) the bodies are fed below the chutes *g* in which are stacked the receptacle closures or lids, the latter being released individually by feed bars *g*¹, carried by arms *g*² connected to the slides and reciprocating therewith so that as the bodies come below the respective chutes the lids are caused to drop directly 70 into position on the bodies. At the base of the closure or lid hoppers *g* are cross bars *j* adjustably mounted by means of slot and bolt connections *j*¹ on standards *j*² extending from the table *a*. Said cross bars carry between them pairs of plates *h*, one pair for each chute, on which are mounted the sides *k*¹ of the chutes. The cross bars *j* also carry 75 guide members *g*³ for the lids, these guide members being spaced apart so as to just support the lids at two diametrically opposite points of the peripheries. The lowermost lid of the stack in the chute *g*, is moved

forward by the feed bar *g*¹ to first die position II the next lid being supported by said feed bar. At position II the guide members carry two oppositely placed plates *h*, mounted by means of slots and bolts *h*¹ and under the action of springs *h*². These plates receive the edges of the lid by means of necks or the like *h*³ so that when the die *c*¹ for the first sealing operation descends the plates are separated by the inclined end *c*¹⁰ of the die and the lid is caused to drop 90 on to the body. 95

The bodies are moved forward to below the first set of dies *c*¹ (position II) which operate to form the first part of the joint, after which the receptacles, so far dealt with, are moved a stage further to under the second set of dies *c*² (position III) which then 100 operate to complete the joint. 105

The slides are reciprocated through dis-

tances corresponding to those between the centres of the chutes and dies and the receptacle bodies are moved from one position to the following one by means of driving pawls 5 m pivoted in the slides f and free, as the slide returns, to pass under the receptacles. The receptacles are held against backward movement on return stroke of the slides by means of spring dogs n located at the sides 10 of the raceways and which will be tripped on the slides returning between strokes.

Other springs n^1 at the sides of the raceways also engage the bodies to prevent return of the receptacles on rearward movement of the slides, these springs being provided at the stepped parts of the slides in advance of the chute and die positions.

Thus a receptacle or row thereof initially lying against the abutment f^1 will be fed 20 forward below the chute g (position I) and at the same time the feed bar g^1 will move the lowermost lid in the chute along the guides g^2 to position II, after which the slide returns to normal; then on the next forward stroke this receptacle will be moved to 25 position II to be acted on by the first die c^1 which latter will cause the lid to pass out of said guides on to the receptacle, the slide then returning, and on a further forward stroke of the slide the receptacle will be 30 moved to position III to be acted on by the second die c^2 and so on continuously, there being always a receptacle or row thereof at the three positions after the first batch are 35 fed.

Finally, the sealed receptacles are moved from position III by following receptacles so far that they may slide on their bases by gravity down an inclined part h on the table 40 and if desired be collected by a conveyor, or they may be turned over after or just previously to leaving the table and roll down an inclined discharge way or be otherwise ejected according to requirements.

45 The receptacles may be passed to the feed slides f either by hand or automatically as by a conveyor with, if necessary, suitable transfer devices, and again the lids may be fed to the chutes g either automatically or by hand 50 in any conventional or approved manner.

The feed slides f are conveniently operated in proper time relation with the dies c^1 c^2 by a cam i mounted on the main drive shaft e , between the die head operating eccentric d^2 , 55 and actuating lever and link mechanism e^1 e^2 connected to the underside of the slides as by means of brackets e^3 with screws e^4 for proper adjustment of the stroke of the slides.

60 The eccentric d^2 are appropriately located outside the side frames supporting the table as shown.

What I claim as my invention and desire to secure by Letters Patent of the United States is:—

65 1. In a machine for applying and sealing

closures to receptacles, a fixed table, a pair of spaced and aligned plungers arranged in superposed relation to the table, reciprocatory means for intermittently feeding receptacles along said table and position the 70 same successively below said plungers, closure carrying means, means for delivering a closure from said closure carrying means to position below the first plunger and in superposed relation to a receptacle positioned 75 on the table relative to said plunger, means carried by said first plunger operative for applying a closure from the closure delivery means to the receptacle and partly seal the same thereto, and means carried by the second plunger operative for completing the 80 operation of sealing the closure to the receptacle.

2. In a machine for applying and sealing 85 closures to receptacles, a stationary bed, a plurality of rows of spaced and aligned plungers arranged in superposed relation to the table, reciprocatory means for feeding receptacles successively along said bed and position the same below said plungers, closure carrying means arranged in advance of the first plunger of each row of plungers, means operative in unison with the receptacle feeding means for feeding closures 90 from said closure carrying means to position below the first plungers, means carried by and operated through the movement of said first plungers for releasing the closures from said closure feeding means, applying the 95 closures to the receptacles and partly sealing the closures thereto, and means carried by said second row of plungers for completing the 100 operation of sealing the closures to receptacles.

3. In a machine for applying and sealing 105 closures to receptacles, a stationary bed, two spaced and aligned plungers superposed to the bed, a reciprocatory stepped slide adapted to intermittently feed receptacle bodies along said bed to position the same 110 successively below said plungers, a closure carrying hopper, reciprocatory means for feeding a closure from said hopper to position below the first plunger, means carried by the plunger operative for removing closures from said feeding means, applying the 115 closures to the body and partly sealing the same thereto, and means carried by said second plunger for completing the operation 120 of sealing the closures to the receptacles.

4. In a machine for applying and sealing 125 closures to receptacles, a stationary bed, two spaced plungers arranged in superposed relation to the bed, a reciprocatory stepped slide adapted to convey receptacle bodies along said bed and position the same successively below said plungers, a plunger carrying hopper, a bar reciprocatory in 130 unison with the feed slide for delivering a closure from said hopper and conveying

the closure to means to releasably support the same below the first plunger, said closure being adapted to be released from said support by means carried by the first plunger, 5 and said means adapted to apply and partly seal the closure to the receptacle body, and means carried by the second plunger for completing the operation of sealing the closure to the receptacle by an axial movement 10 of the plunger only.

5. In a machine for applying and sealing closures to receptacles, a stationary bed arranged with a raceway, two spaced and alined plungers arranged in alinement above 15 the raceway in the table, a slide reciprocable longitudinally of the raceway, pivoted pawls carried by said slide to engage and advance the receptacle bodies in the raceway during the forward movement of the slide to 20 successively position the bodies below the plungers, said pawls being adapted to pass under the bodies during the return movement of the slide, pivoted spring influenced dogs to have movement laterally into and 25 out of the raceway and normally urged to position in the raceway, said dogs being adapted to be moved out of the raceway by the bodies during the advancing movement thereof and to engage at the rear of 30 the bodies to prevent retrograde movement thereof with the slide, a closure carrying hopper, means reciprocatory in unison with the slide for delivering a closure from the hopper, releasably supporting and conveying the closure to position below the first plunger, means carried by said plunger to 35 release a closure from said closure conveyer and supporting means, apply the closure to the body and partly sealing the same thereto,

and means carried by the second plunger 40 for completing the operation of sealing the closure to the receptacle by an axial movement of the plunger only.

6. In a machine for applying and sealing closures to receptacles, a fixed table, a pair 45 of spaced and alined plungers arranged in spaced relation to the table, closure carrying means, and reciprocatory means for delivering a closure from the closure carrying means and position the same relative to the first plunger and simultaneously position a receptacle below said closure and plunger, said plunger carrying means for applying the closure from said means to the receptacle and partly sealing the closure thereto, and 50 said closure and receptacle delivery means then being operative to position the receptacle with the partially sealed closure to the second plunger, and said latter plunger carrying means for completing the closure 55 sealing operation.

7. A machine for applying and sealing closures to receptacles as claimed in claim 1, wherein the closure and receptacle delivery means is operative in unison to deliver a 60 closure and receptacle to the first plunger when a receptacle with the partially sealed closure is delivered from said plunger to the second plunger, and to deliver the completely sealed receptacle from the second 65 plunger during the successive movement thereof and during said movement advancing a partially sealed receptacle to the second plunger and delivering a closure 70 and receptacle to the first plunger. 75

In witness whereof I have signed this specification.

GEORGE WILLIAM BERRY.
